CLARK EDWARD HARRISON, OF ATLANTA, GEORGIA.

CARD GAME.

Application filed April 24, 1925. Serial No. 25,521.

To all whom it may concern:

Be it known that I, CLARK E. HARRISON, a citizen of the United States, residing at Atlanta, in the county of Fulton and State 5 of Georgia, have invented certain new and useful Improvements in a Card Game, of which the following is a specification.

The present invention relates to card games.

10 The object of the invention is to provide a card game which is easy to learn, interesting and highly amusing, and yet which involves enough "fine points" to make the player's attention, alertness and resourcefulness a large factor in his success.

Referring to the accompanying drawing for a particular description of the cards embodying the invention and of the method of playing the game, there is illustrated a 20 series of sixteen cards. The first four cards of the series bear the letters "S", "T", "A", "R", the cards when arranged in the sequence illustrated spelling the word Star. The fifth card of the series bears a hyphen. 25 The next eight cards bear the letters "S", "A", "L", "E", "S", "M", "A", "N", spelling when arranged in proper sequence the word Salesman. The first thirteen cards of the series, therefore, are adapted to spell 30 the compound word Star-Salesman. The fourteenth card of the series bears the picture of a young man representative of the genus salesman. The fifteenth card depicts, or is designed to depict, an attractive 35 young lady, representative of the modern "vamp". The sixteenth card bears the picture of a man in a circular frame with the five projecting points of a star indicating a star salesman. In addition to the letters 40 and pictures each card bears a numeral to indicate its place in the sequence.

The game is ordinarily played with a single deck of 145 cards, consisting of four cards bearing pictures of young ladies, or 45 vamps, one card bearing the picture of a star salesman, and ten series, or sets, each composed of the first fourteen cards shown on the drawing.

50 From two to eight persons may play the game. After shuffling the cards thoroughly, a hand of five cards is dealt to each player and then the remaining cards of the pack are disposed in groups of five and arranged criss-cross in a stack at the center 55 of the table face down.

The first player at the left of the dealer may start the game by placing the first letter of the word "Star-Salesman" on the table face up and he may continue to play 60 as long as he can play the cards in proper order to spell the word "Star-Salesman". When he can no longer play or if he does not have the first letter of the word he must lay one card down and call out the word 65 "pass" signifying that he can no longer play. Then the next player to the left takes up the play if he has the proper card or cards and so on around.

The piles build up to fourteen cards by 70 spelling the word "Star-Salesman" and by placing a picture of a salesman thereon after the completion of the word. The player who has completed a pile takes it off with a 15-point count, for example, unless 75 one of his opponents should have in his possession a vamp, that is, a card bearing the picture of a young lady. If he has a vamp he can call out the word "Vamped" and place his vamp on top of the pile and take 80 it with a 25-point count, for example, unless the player who finished the pile by placing the salesman on it should have in his possession a vamp also. If he has a vamp he presents it and retains his pile 85 with a 25-point count and the opponent withdraws his vamp and holds it for a future play. Should a player hold the star salesman he may call out the word 90 "Star-Salesman" and present the card and take the pile with a 75-point count, for example. The star-salesman, however, can be used only in case the vamp has been played by an opponent. In case a player 95 is vamped or the star-salesman is used to take his count he can neither make another play or reserve but must pass.

When a player can no longer play he lays down one card face up in front of him. The letter beginning the word "Star-Salesman" should be placed well to his left and the card bearing the picture of the salesman should be placed well to his right, then he 100 should build in between these cards with his other cards placing them in their consecutive order. All like cards should be placed in one pile giving a total number of 5 fourteen piles in a player's reserve.

It is a rule of the game that all cards bearing the capital S with the small figure 1 in the corner must be played first by placing them face up separately on the table. 10 Should a player at any time during the game play another card out of his hand or off of his reserve before playing this card any of his opponents have the privilege of calling out the word "sold". The first 15 player observing the omission to play this capital S card may call out the word "sold" and thereby be given the right when his turn comes to play any card off the reserve of the player who has failed to play the 20 capital S card.

Should a player have in his hand a picture of one of the girls or of the star-salesman he should make no intimation whatsoever of having such card but should conceal 25 that fact by every means possible. This is his privilege and a very important point in the game. These are the only cards which the player has a right to conceal.

The object of the game of course is for the 30 individual players or partners to reach the required number of points. The science of the game lies in carefully observing the board and the reserve of all players.

Now having described my invention what I claim as new and desire to secure by 35 Letters Patent of the United States is:

1. A deck of playing cards, comprising a plurality of sets, each set including a series of cards each card bearing a single letter of the alphabet, the letters being so chosen as 40 to spell the name of an object when the cards are arranged in a certain sequence, each set also including a single card bearing a picture representing the genus of the object spelled, a single card bearing a picture of 45 the specific object and a single card having an arbitrary designation.

2. A deck of playing cards, comprising a plurality of sets, each set including a series of cards each card bearing a single letter 50 of the alphabet, the letters being so chosen as to spell the word Star-Salesman when the cards are arranged in a certain sequence and each card also bearing a numeral to designate its place in said sequence, each 55 set also including a single card bearing the picture of a salesman, a single card bearing the picture of a star salesman and a single card bearing the picture of a young lady.

In testimony whereof I hereunto affix my 60 signature.

CLARK EDWARD HARRISON.
